UNITED STATES PATENT OFFICE.

SCHUYLER S. CASE, OF PHILADELPHIA, PENNSYLVANIA.

FOLDING TABLE.

SPECIFICATION forming part of Letters Patent No. 356,618, dated January 25, 1887.

Application filed November 9, 1885. Serial No. 182,281. (No model.) Patented in Canada May 27, 1884. No. 19,416.

To all whom it may concern:

Be it known that J, SCHUYLER S. CASE, a citizen of the United States, residing in the city and county of Philadelphia, State of Pennsylvania, have invented a new and useful Improvement in Folding Tables, which improvement is fully set forth in the following specification and accompanying drawings, in which—

Figure 1 represents a side elevation of a folding table embodying my invention. Fig. 2 represents an end elevation thereof in folded condition. Fig. 3 represents a side elevation thereof in folded condition. Fig. 4 represents a top view of a detached portion. Fig. 5 represents a horizontal section in line $x-x$, Fig. 1.

Similar letters of reference indicate corresponding parts in the several figures.

My invention consists of a table which may be folded in compact form, as will be herein-after fully described.

Referring to the drawings, A represents the legs of a table, each formed of the crossed pieces B and top and bottom connecting pieces, C D.

E represents metallic sockets, which are secured to the cross-pieces C D, respectively, and face each other, forming bearings for the upright pieces F of the frame of the table, said pieces, it being seen, having pivotal motions in the sockets E. Secured to the pieces F is the brace G of the frame, the same being formed in sections, which are connected by a hinge, H, so that the sections may be folded against each other, as seen in Figs. 2 and 3.

In order to hold the sections in extended position and render the brace rigid, I secure to the inner end of each section a lug, J, which projects laterally, the two sections occupying coincident places at the side of the brace, whereby they may be embraced by a dog or catch, K, and thus locked together, preventing the sections from separation.

The dog K is pivoted to one of the sections of the brace, and when thrown back it may be rested on a pin or stop, L, on the brace, in which position the lugs J are released of the dog, and the sections of the brace may be folded.

The hinge H, of which there is one on each of the upper and lower sides of the brace G, con-

sists of plates H', which are screwed or otherwise secured to the sections, and a plate, H'', which is pivoted at each end to the plates H'. This allows the greatest freedom of motion of the hinge and permits the sections to fold flat 55 against each other.

Rising from the cross-pieces C of the legs are spurs M, which are slotted and secured in position by the screws N, whereby the spurs may be vertically adjusted, as desired, said 60 spurs being adapted to pierce the top P of the table, and hold the same in position while it rests on the legs.

Projecting laterally from one of the pivotal pieces F is an eye or perforated lug, Q, and 65 secured to the opposite piece is a spring-catch, R, the nose or pin R' of which is adapted to enter the eye Q when the sections of the brace are folded. The brace G and pivotal pieces F are connected by braces S for strengthening 70 purposes.

It will be seen that when the parts are in position shown in Fig. 1 a convenient table is formed. For laundry purposes the table-top may be raised at one end for ironing shirts, 75 the spur at the opposite end serving as a pivot and preventing displacement of the top at said end.

In order to fold the table the top is removed, 80 the dog K thrown back from the lugs J, the sections of the brace G are folded against each other, and the legs A turned at a right angle from the position shown in Fig. 1, the latter being permitted owing to the pivotal connection of the legs with the upright pieces F. 85 The catch R is now engaged with the eye Q, thus locking the sections of the brace and preventing unfolding or separation of the parts. (See Figs. 2 and 3.)

By releasing the catch and eye the sections 90 of the brace and the legs may be unfolded and restored to their operative position. The dog K is moved to engagement with the lugs J, thus locking the sections of the brace, and when the top is placed on the legs and held by 95 the spurs M the table is in condition for service.

Having thus described my invention, what I claim as new, and desire to secure by Letters Patent, is—

1. A folding table having crossed legs with connecting-pieces, uprights pivoted to said connecting-pieces, and a sectional brace connected to said uprights, substantially as described.
2. In a folding table, a sectional brace secured to uprights pivoted to connecting-pieces of the legs, and provided with lugs and a catch, substantially as described.
3. In a folding table, the sectional brace G, secured to a pivoted upright, and having each section provided with plates H, and said plates being joined by plates H², substantially as described.
4. In a folding table, the cross-legs A, with connecting-pieces C and D, the uprights F, pivoted to said pieces C and D, one of the said uprights having an eye, Q, and the other having a catch, R R', and the sectional brace G, all of said parts being arranged and combined substantially as described.
5. A brace, G, formed of sections connected by a pivotal or hinged plate, H², each section

being provided with a lug, J, both of which are engaged by a dog, K, which is connected 25 with one of the sections, substantially as described.

6. In a folding table, a frame pivotally connected with the legs, and consisting of a sectional brace and upright pieces, the sections 30 of the brace being hinged or pivoted to each other and connected with the upright pieces, and provided with fastening devices, the upright pieces being pivotally fitted in sockets in the cross-pieces of the legs, substantially as 35 described.

7. The legs A, the pivotal pieces F, and sectional hinged brace G, fastening lugs and dog J K for the sections of the brace when extended, and fastening eye and catch Q R for 40 said sections when folded or closed, substantially as and for the purpose set forth.

SCHUYLER S. CASE.
